UNITED STATES PATENT OFFICE.

GEORGE B. WIESTLING, OF MONT ALTO, PENNSYLVANIA.

FURNACE FOR REFINING IRON.

SPECIFICATION forming part of Letters Patent No. 359,700, dated March 22, 1867.

Application filed May 19, 1865. Serial No. 166,031. (No model.)

To all whom it may concern:

Be it known that I, GEORGE B. WIESTLING, a citizen of the United States, residing at Mont Alto, in the county of Franklin and State 5 of Pennsylvania, have invented certain new and useful Improvements in Furnaces for Refining Iron, of which the following is a specification, reference being had therein to the accompanying drawings.

10 My invention relates to that kind of furnace generally known as a "knobbling-fire," "forge-fire," or "bloom-furnace," but more properly it is a Lancashire hearth or charcoal blomary furnace or forge-fire, in which pig-iron, 15 run-out metal, or wrought scrap-iron is melted with charcoal fuel urged by either a hot or cold blast of air by which the metal is oxidized, decarbonized, sank, and refined by the action of the blast; and my improvement upon the 20 furnace consists in a different construction of some of its parts and the addition of other parts, whereby a great saving of labor, metal, time, and a more uniform quality of iron is the result of such change, as will be fully 25 hereinafter described.

In the drawings, Figure 1 represents a side view of the furnace. Fig. 2 represents an upright sectional view of same. Fig. 3 represents an upright transverse view, partly in 30 section, on line xx of Fig. 2, and Fig. 4 represents a horizontal view, partly in section, on line yy of Fig. 2.

A represents the usual bed-plate having the water sink or well a , which is supplied with water from a pipe or trough, a' , through apertures a'' and the waste water to pass off at a''' , as seen in Fig. 3. Upon the bed-plate A is 35 built the side walls, A' , and front wall, A'' , of the furnace.

40 B is the puddling or refining hearth over the water-sink a in the bed-plate A, the hearth being quadrangular in form and consisting of bottom plate, tuyere iron plates, and cinder-hole plate on or in which the refining of the iron is done.

45 b represents the charcoal, b' its height, and b'' the iron on the hearth.

The front of the furnace has the usual opening for charging the oven with the iron to be 50 refined, closed by gate A^4 , hinged to the front wall, and other openings necessary and usual

in this kind of furnace for charging the hearth with charcoal and for working or manipulating the lump of fused or plastic metal on the charcoal, and for other purposes necessary to 55 this kind of hearth. These openings may be closed by proper gates, if necessary, and the gates have openings through which the bar for lifting the mass can be operated, or "buckstaves" may be used instead of gates. 60

B' is a shelf or oven-bottom in the upper and rear part of the furnace, has a slight inclination downward as it extends toward the front of the furnace, and this shelf receives the metal b'' that is to be acted upon and refined, 65 which metal is placed upon the shelf B' through the opening A'' by a proper instrument.

C represents an arched roof over the furnace extending from front to rear and to the flue 70 or stack, and C' is an outer arched plate over roof C, leaving a space or chamber C'' between the two plates or roofs C and C' . These two arched roofs are formed from curved metallic plates, or of two flat or corrugated plates having the blast-chamber C'' between them, which 75 is closed air-tight at both its ends.

D is the pipe through which the forced blast of air is blown into chamber C'' direct; or the blast may be divided, so that a portion will be 80 forced to pass through a branch pipe, D' , to be delivered into the front part of chamber C'' by turning the cut-off valve d in pipe D and valve d' in branch pipe D' , or the whole blast can be forced through branch pipe D' into the 85 chamber C'' , when required, by closing valve d and opening valve d' .

E E are bent pipes on opposite sides of the furnace, with their upper ends bent, and pass through the outer arched plate, C' , of the roof 90 to connect with chamber C'' , toward the rear end thereof, bending downward the proper distance, then turn horizontally toward each other, and at a short distance apart terminate in tuyeres E' , that enter the furnace through a removable plate, F, in the rear or back wall of the furnace, in apertures ff in plate F and opposite the plastic metal.

E'' E'' are bent pipes on opposite sides of the furnace, with their upper ends bent, and pass through the outer arched plate, C' , of the roof, bending downward the same distance as do 100

pipes E, then bend toward each other, terminating in tuyeres E'', which enter the furnace through apertures f' f' in the removable tuyere-plates F', on opposite sides of the furnace, which 5 gives a blast of air on opposite sides and toward the front of the furnace, to force air directly upon opposite sides of the plastic metal. This description of the construction of the furnace shows the blast of forced air applied 10 upon three sides or directions to impinge against and act upon the fused or plastic metal in three directions; but without departing from the principle of my invention blasts of air can be made to act upon the iron on the fourth, or 15 any number of sides that the furnace may have.

In order to clear the outside of the nozzles of the two rear tuyeres, E', of adhering cinders or clinkers, holes f'' are made in the removable tuyere-plates F' in line with the nozzles, through which holes an implement is forced that will remove such cinders or clinkers or other obstructions to their complete action and efficiency.

The two side tuyeres are kept clear from 25 cinders by passing the implement through a front opening in the furnace.

In order to clear the inside of the tuyeres and prevent cinders from obstructing a full blast through them, I construct a device by 30 which a direct communication through the inside bore of the tuyeres is had, and with a rod of iron of proper size all cinders or obstructions in the tuyeres will be forced out of the bore of the tuyeres into the fire. This device is constructed as follows: A metal loop, e, is placed around the angle-union e' and secured in position, with a lever, e'', pivoted thereto to rise and turn up out of the way. Lever e'' has a weight, e''', at its outer end. A 35 lug, 1, depends from the under edge the lever, having a stopper, 2, pivoted at 3 to lug 1, the stopper having a convex inner end to fit into the countersink in the outer end of the bore in tube 4, that is screwed into the angle-union e'. This construction gives a straight opening 40 from the outside through tube 4 and the tuyere, so that a bar of iron of the proper size will pass through the tube and tuyere and will force all obstructions out of the inside of the 45 tuyere into the furnace. Tube 4 being countersunk at the outer end of its bore and the stopper 2 convex on its inner end will always insure a tight joint, even when the bore in the tube is worn to be irregular in its shape by the use of the cinder bar or poker, and when the lever e'' is down in a horizontal position the weight e''' is sufficient to overbalance the pressure of the air-blast in the blast-tubes and maintain an air-tight joint while in that position. 50 By having the stopper pivoted to the lug 1 it becomes self-adjusting to the countersink in the tube without further attention from the attendant other than turning it over to its normal position.

65 G is the "fore-plate" in the front of the hearth, over which the fused metal is manipu-

lated by a proper bar or implement. It has the proper rabbets at each end to admit it to enter the opening in the front wall of the furnace a proper distance.

g g are upwardly-rising flanges, one at each end of the plate.

g' g' are notches in the front edge of the table to receive a projecting part of a supporting bracket.

H H are metal removable brackets for the support of the fore-plate G—one at each end—and having at their rear edges a dovetail enlargement, h, and at their upper forward corners projections h' h', to fit into notches g' in the 80 fore-plate.

I I are projecting lugs attached to the front of the furnace in pairs to receive the dovetails h on the rear edges of the brackets and securely hold them to the front, and I' I' are 85 pairs of steady-blocks, between which the forward edges of the brackets are held in place upon the bed-plate A. This construction of the fore-plate and its supports gives a cheap and strong table to work over, and a table that 90 can be quickly and easily removed from the furnace-front when necessary.

In order to distinguish the difference between what is described as my improvement and furnaces or hearths in common use, it is 95 proper to state that the Lancashire hearth and others have substantially the same bed-plate with water underneath, suitable inlet and discharges, by which the water can freely flow, during the working of the furnace, in keeping 100 the hearth cool. Either cold or hot blast is used, and a single tuyere, and in some instances two tuyeres, are in use, to direct the blast of air against the molten or plastic metal, with charcoal on the hearth around and above the 105 tuyeres, a plate in the oven to receive the metal to be preheated, and heat generated and applied, and working-tables used, over which the ball of metal is manipulated in its treatment, that the metal to be operated upon is 110 placed upon an inclined shelf, B', and the heat and blast generated and applied in the usual way. The metal is heated on the shelf, is brought down, and as it is fused drops through the charcoal in contact with the blast of air 115 from the tuyeres, when it will become partially oxidized. By the action of the oxide of iron thus formed and of the basic silicate of protoxide of iron remaining in the hearth the metal is decarbonized to a certain extent, and in consequence becomes less fusible and more pasty, and after complete fusion the refining of the metal commences, which consists in incessantly breaking up the lump of metal by a bar of iron and carrying the metal toward the tuyeres, the 120 raw portions of which, being more highly carbonized and more fusible than the rest, always run down to the bottom and there harden. The metal which has thus been more or less decarbonized is again broken up and again submitted to the action of the blast until it is all 125 sufficiently refined and even in texture and 130

quality, after which all the metal is brought to the top of the hearth, and is again melted down with a lively heat, to be formed into a ball or lump, when fresh charcoal is thrown 5 into the hearth, the heat and blast on the un-melted portions being kept up at intervals with the iron bar to prevent their adhering to the lump before being melted. The lump is then taken out to be hammered into a prismatic 10 shape or bloom.

The principles upon which this method of refining iron and its chief advantage are that the rawer portions of the metal melt down in drops, or liquefy, and so become separate from 15 that already fully refined by the blast; and in so liquefying it becomes exposed to the oxidizing action of the blast, and is more or less decarbonized, the fully refined metal remaining aloft all the while. The mass or lump of metal 20 being thus properly, thoroughly, and equally refined, and in the final running down in a coherent lump the slag separates from the refined iron, and if present in an injurious degree it may be tapped out.

25 The blast is used at a temperature of 212° to 400° Fahrenheit, and at a pressure of two and one-half inches of mercury.

I have described the construction of my hearth or my furnace for refining iron, and 30 given the description and the operation of the "Lancashire hearth," and modifications in ordinary use, and with all these described processes the action of the blast and its effects upon the fused metal is, with the manipulation 35 of the metal, the refining agent, and if from lack of skill or faithfulness, or for any cause the workman fails to bring all the metal over and above the tuyeres, so as to receive the proper action of the blast upon the metal, then 40 the lump is not equally refined, but it is raw or unrefined iron, and such will be found in the lump. Even with the most expert manipulation and care there is a difference in the 45 quality of the iron in the lump; that on the side next the tuyere, where but one tuyere is used, is always the best, or better than that on the opposite side, which becomes manifest when the lump is under the hammer, where the unrefined iron falls from the lump as hammer-scales and lessens the yield of metal.

50 I am aware that an improvement upon the one-tuyere blast has been made and is in use where two tuyeres are used to give the blast upon opposite sides of the hearth or fire, and 55 that such hearth or fire has two opposite openings and tables or fore-plates, always necessitating two workmen to manipulate the metal before the blast at the same time and from opposite sides of the fire. Such improvement 60 lessens the production of raw or unrefined iron, but it adds to the expense of both fuel and labor, as two workmen are employed, where by my hearth or fire but one workman is employed.

65 My improvement, then, consists in the shell of the fire being so constructed that blasts of

air under pressure, either hot or cold, can be introduced through tuyeres on three or more sides of the fire, and having but one fore-plate, G, for a single workman, the advantages of 70 which are manifold, both in fuel and labor, as—

First. It reduces the probabilities of raw or unrefined iron to a minimum, as every particle treated is more surely and easily brought 75 into contact with the action of the blast, when such blast is applied upon three or all of its sides, than when but one or two sides are so acted upon by the blast; hence the whole mass is more uniformly acted upon and refined.

Second. The process is expedited. The output of refined iron from the same sized hearth in the same time is about thirty-seven per cent. greater than when the blast is given on one side, and also greater than when blasts are 85 given on two sides with two or more workmen manipulating the lump at the same time.

Third. The fuel is more uniformly consumed, performing better duty, and resulting in a great saving in the quantity of charcoal consumed per ton of blooms.

Fourth. The entire lump being properly and uniformly refined, there is less falling away at the hammer, less waste, substantially none at all, resulting in a material economy or saving 95 of metal.

Fifth. A larger mass of metal can be manipulated and be refined at a time, if desirable, than is practicable with an ordinary fire, as heretofore used with one or two blasts, which 100 always resulted in a lump of unequally-refined iron.

Sixth. This improved construction of the fire or hearth works equally well with hot blast or cold blast.

105 My improvement further consists in the construction of the roof of the furnace, which is formed of two arched metallic plates with an air space or chamber between them, or of two flat or corrugated plates with a space between them, through which space or chamber the blast is made to pass on its way to the tuyeres. The constant flow of air under pressure between the plates protects them, which will materially prolong their existence, while in the 110 passing of the air through the space between the plates the blast of air absorbs heat from the plates, and is by this means converted into a hot-air blast. The heating of the air in this manner interferes less with the free passage of 115 the blast toward the tuyeres than when the air is heated in the usual siphon-pipes, as the passage is less tortuous and the construction 120 less expensive. If a more intense heat is desirable than this gives, deflection-plates placed 125 inclined in the space between the plates can be used, as seen in dotted lines, Fig. 2, as X, creating a more tortuous circulation of the air over the plates or between them.

130 As ordinarily constructed, the roofs of refining-fires are made of cast-iron plates or "sows," or of an arched or flat fire-brick cov-

ering, either of which methods are objectionable by not being durable, and hard to replace.

I have heard that an iron box had been used as a cover, the box being either open at top 5 or closed and a circulation of water maintained therein to protect the cover from destruction. The objectionable feature in this is that if a leak occurs in the box the water will go into the fire, and such an overhead quantity would 10 result in a dangerous explosion.

I am aware that blasts of air have been introduced from three or more directions into blast-furnaces and cupolas for the purpose of 15 promoting the combustion of fuel in the smelting of ores and melting iron. I am also aware that blasts of air from several different directions have been introduced into a mass of 20 molten metal in a converter for converting the mass into steel.

20 I am further aware that air has been and is now introduced from two directions only into a charcoal blomary furnace or forge-fire for the purpose of eliminating the metalloids. The introduction of air in this way from only 25 two directions requires more skill and faithfulness of the workman to secure the action of the blast on the molten drops of metal, and at best allows many of such molten drops to escape the contact and action of the air, and 30 always has and does still result in unreliable and unequal refining, in slow work, and extravagant cost.

I wish to confine my claim to the invention as it is applied to charcoal blomary furnaces 35 or forge-fires, and in the construction of such furnaces as will permit an increased number of air-blasts and from different directions into the hearth, thus insuring a blast of air in contact with all the molten drops of metal to be 40 more surely, more easily, uniformly, quickly, and economically effected by the oxygen of the air, which deprives the metal of impurities and converts it into malleable or wrought iron. It expedites the process of refining the 45 metal. The consumption of fuel, waste, and labor are lessened, all being accomplished by my improved introduction of blasts of air into the hearth of a charcoal blomary furnace or forge-fire, and which has never, as I believe, 50 been done before in such a furnace.

Having thus fully described my invention,

what I claim, and desire to secure by Letters Patent, is—

1. In a charcoal blomary furnace or forge-fire, the combination of the plates C and C', 55 forming an air-chamber, C'', between them, the direct air-supply pipe D, connected with the chamber C'' through plate C', the outgoing air-pipes E E'', terminating in tuyeres E' and E'', plates F F', and single working-front, all 60 constructed substantially as described.

2. In a charcoal blomary furnace or forge-fire, the combination of plates C and C', forming an air-chamber, C'', between them, the direct air-supply pipe D, having turn-valve d 65 therein, branch pipe D', having valve d' and connecting with air-chamber C'', blast-pipes E E'', terminating in tuyeres E' and E'', plates F and F', and single working-front, constructed 70 substantially as described.

3. In a charcoal blomary furnace or forge-fire, the combination of the three side walls provided with tuyere-openings, the arched plates C and C', forming an air-chamber, C'', between them, with the inlet air-pipes D and D' and 75 exit air-pipes E E and E'' E'' and their tuyeres E' and E'', substantially as described.

4. In a charcoal blomary furnace or forge-fire, the combination of a single working-front, three side walls having tuyere-openings, as described, with the air-pipes E E, 80 tuyeres E' E', air-pipes E'' E'', and tuyeres E'' E'' E''', constructed and operating substantially as described.

5. In a charcoal blomary furnace or forge- 85 fire, the removable metal brackets H, having dovetail edges h, in combination with the lugs I, that receive the dovetail edges on the brackets, and the steady-blocks I', all constructed to operate substantially as described. 90

6. In a charcoal blomary furnace or forge-fire, the fore-plate or table G, having notches g' in its front edge, in combination with the removable brackets H, having the upwardly-projecting points h', in the manner substan- 95 tially as described.

In testimony whereof I affix my signature in presence of two witnesses.
